PROTECTIVE STORAGE CARRIER FOR A MACHINE KNIFE

Robert I. Becker, Paxton, and Edward J. Stephens, North
Attleboro, Mass., assignors to L. Hardy Company,
Worcester, Mass.

Filed Apr. 25, 1974, Ser. No. 463,994

Term of patent 14 years

Int. Cl. D3—02

U.S. Cl. D87—1 R

FIG. 1 is a front perspective view of a protective storage carrier for a machine knife showing our new design;

FIG. 2 is a right end elevational view;

FIG. 3 is a top plan view;

FIG. 4 is a rear elevational view; and

FIG. 5 is a bottom plan view thereof.

We claim:

The ornamental design for a protective storage carrier for a machine knife, as shown.
